UNITED STATES PATENT OFFICE.

WILLIAM WELLS CAVERLEY, OF VANCOUVER, BRITISH COLUMBIA, CANADA.

PENCIL-SHARPENER.

1,317,685.

Application filed December 4, 1917. Serial No. 205,367.

Patented Oct. 7, 1919.

To all whom it may concern:

Be it known that I, WILLIAM WELLS CAVERLEY, a subject of the King of Great Britain, and a resident of the city of Vancouver, 5 in the Province of British Columbia, Canada, have invented certain new and useful Improvements in Pencil-Sharpener, of which the following is a specification.

My invention relates to improvements in 10 pencil sharpeners, and the object of my invention is to provide a device of this nature adapted to be carried personally with and on the pencil so as to be handy and convenient for the sharpening of the same and 15 which device is simple, useful, and inexpensive.

I attain this object by the construction illustrated in the accompanying drawings in which—

20 Figure 1 is a front view of my device mounted on a pencil.

Fig. 2 is a side view of Fig. 1.

Fig. 3 is a vertical cross sectional view of the device, taken through the center line.

25 Fig. 4 is a side view of the eraser element.

Fig. 5 is a view of the opposite side of the eraser element shown in Fig. 4.

Similar figures of reference indicate similar parts throughout the several views.

30 The device consists of a tubular member 1, formed of suitable material, closed at its upper end to form a revoluble cap for the end of a pencil 23 and in the interior of which at its upper end is secured in any 35 suitable manner a cutting blade 2, the edge of which blade is disposed so that the end of the pencil when inserted and pressed into the member 1 will be sharpened thereby when the member 1 is rotated. As it is intended

40 that the device be carried personally with the pencil it is necessary to provide for its detachable connection thereto and this is effected by securing an encircling band 3 on the outside of the member 1, the band being 45 divided and threaded through two pairs of slots 4—5 and 6—7 respectively cut through the wall of the member 1 on opposite sides of the same and being turned outwardly at its ends to form lugs 8 and 9 through which

50 a pin 10 is passed and riveted over on each end to draw the band tightly on to the member 1, on which pin is fulcrumed a lever 11 the upper end of which is adapted to bear on and press inwardly a flexible strip 12 formed 55 on the member 1 by the cutting of two slots

13 and 14 in the wall thereof, such inward pressure being produced by the act of inserting the pencil and sharpener into the pocket so that the edge of the same passes between the periphery of the member 1 and the lower 60 end of the lever 11, from which it will be seen that the strip 12 will then bear on the pencil to prevent the detachment of the sharpener therefrom, but that when the pencil is removed from the pocket the pressure on the strip will be relieved, allowing the member 1 to be rotated to sharpen the pencil if desired.

15 and 16 indicate a pair of jaw members formed on the end of member 1 adapted to 70 form a finger grip for rotating the sharpener, between which jaws is adapted to be inserted an eraser element 17 to the lower edge of which is secured a metal clip 18 provided on one side with projections 19 and 75 20 adapted to co-act springably with sockets 21 and 22 formed on the inner face of jaw 15 so as to detachably secure the eraser element in place between the jaws 15 and 16.

From the foregoing it will be seen therefore that I have devised a simple, effective, and inexpensive pencil sharpener which, on account of its being carried on the pencil in the form of a cap, as it were, is of great convenience and usefulness.

85 What I claim as my invention is:

1. A pencil sharpener comprising, a revoluble cap adapted to inclose a pencil end and provided with an interior cutting blade, an integral flexible strip formed in the wall 90 of the cap and a lever mounted on said cap capable of being operated to force the flexible strip of the cap inwardly against the pencil.

2. A pencil sharpener comprising, a revoluble cap adapted to inclose a pencil end provided with an interior cutting blade and an integral flexible strip on one side, and a suitably fulcrumed lever mounted on said cap adapted to co-act with said strip and 100 capable of being operated to force said strip against said pencil.

3. A pencil sharpener comprising, a revoluble cap adapted to inclose a pencil end provided with an interior cutting blade and a 105 depressible strip on one side, an encircling band secured to said cap, and a lever fulcrumed on said band and adapted to control the depression of said strip.

4. A pencil sharpener comprising, a revol- 110

luble cap adapted to inclose a pencil end provided with an interior cutting blade and a depressible strip on one side, said cap being also provided on opposite sides with two pairs of slots, a divided band threaded through said slots and encircling the cap, the ends of said band being turned outwardly, a pin securing said ends to-

gether, and a lever fulcrumed on said pin, the upper end of said lever being adapted to 10 control the depression of the said depressible strip.

Dated at Vancouver, B. C., this 21st day of November, 1917.

WILLIAM WELLS CAVERLEY.
